UNITED STATES PATENT OFFICE.

BERNARD B. BRASZKOWSKI, OF PITTSBURGH, PENNSYLVANIA.

MOLD.

1,310,172.

Specification of Letters Patent. Patented July 15, 1919.

Application filed September 12, 1918. Serial No. 253,816.

To all whom it may concern:

Be it known that I, BERNARD B. BRASZKOWSKI, a citizen of the United States, residing at Pittsburgh, in the county of Allegheny and State of Pennsylvania, have invented certain new and useful Improvements in Molds, of which the following is a specification.

This invention relates to molds for use in connection with open-hearth furnaces, and has for its object to provide a mold for such use, in a manner as hereinafter set forth, for making a solid ingot and overcoming piping to a minimum.

15 A further object of the invention is to provide a mold for open-hearth furnaces including a removable head and jacket, whereby when either or both have been injured, a new head or jacket or both can be substituted, under such conditions overcoming the necessity of discarding the body portion of the mold.

25 A further object of the invention is to provide a mold for open-hearth furnaces having lifts arranged in a manner as hereinafter referred to, to overcome the breaking off of the mold at the top when the mold is lifted.

30 Further objects of the invention are to provide a mold for use in connection with open-hearth furnaces which is simple in its construction, strong, durable, efficient and convenient in its use and comparatively inexpensive to manufacture.

35 With the foregoing and other objects in view this invention consists of the novel construction, combination and arrangement of parts as hereinafter more specifically described and illustrated in the accompanying drawings wherein is shown an embodiment of the invention, but it is to be understood that changes, variations and modifications can be resorted to which come within the scope of the claims hereunto appended.

40 In the drawings wherein like reference characters denote corresponding parts throughout the several views:

Figure 1 is an elevation of a mold in accordance with this invention.

45 Fig. 2 is a vertical sectional view thereof. Referring to the drawings in detail 1 denotes the body portion of the mold and which is formed of steel. The body portion 1 in plan is preferably rectangular and each wall thereof gradually decreases in

thickness from its lower to near its upper end, or in other words the outer face of each wall of the mold inclines upwardly and inwardly from the bottom thereof to a continuous lateral flange 2, at the top of the 60 body portion 1. The flange 2, is cutaway to provide a peripheral shoulder or ledge 3.

The inner face of each of the walls of the body portion 1 is plane throughout, with the exception that in proximity to the top 65 thereof such face is cutaway to form a shoulder or ledge 4, to support the brick, not shown, which extends into the head. The latter will be presently referred to.

Arranged within the body portion 1 is a 70 cast iron jacket 6 which provides a molding cavity or chamber 8. The jacket 6 has a peripheral shoulder 9, which is flush with the lower end of the body portion 1. The jacket 6 extends to and is flush with the 75 shoulder or ledge 4, and its top edge is used in connection with the shoulder or ledge 4, to support the brick, not shown.

The jacket 6 projects below the body portion 1, and is inclosed by a collar 5, which 80 abuts against the lower end of the body portion 1 and the shoulder 9. The body portion 1 has a plurality of pockets 11, with which communicate openings 12, these latter registering with slots 13, formed in the 85 collar 5. The slots 13, open into pockets 14. The pockets 11, openings 12, slots 13 and pockets 14, are provided for the purpose of positioning connecting bolts 15, relative to the body portion 1, and collar 5, whereby 90 the latter will be connected to the former.

Mounted upon the shoulder or ledge 3, is a removable rectangular head 16, formed of cast iron and which incloses the major portion of the flange 2, as clearly shown in 95 Fig. 2.

Upwardly extending yokes 17, are provided in the top edge of the head 16, to facilitate the removal and replacements of said head 16, when required.

100 Arranged below the flange 2, are laterally projecting apertured lugs 18, to which are pivotally connected as at 19, yokes 20, to facilitate the shifting of the body portion 1, when required.

105 The lugs 18, are arranged below the flange 2, and by such an arrangement when the body portion 1 is lifted the weight is off flange 2, preventing the possibility of breaking of said flange 2.

The top edge of the jacket 6, and the ledge 4, supports a body of brick which is extended into the head 16, and forms a continuation of the molding chamber, charcoal 5 supports the brick for the purpose of keeping it hot so that when the metal runs into the head it will not cool rapidly and piping will be prevented.

As the head is removable, it is obvious 10 that if it becomes damaged a new one can be substituted, under such conditions doing away with the throwing away of the body portion as would be the case if the head were an integral part of the body portion. 15 This statement also applies to cast iron jacket 6 if the latter should become injured.

What I claim is:

1. A mold for the purpose set forth comprising a hollow metallic body portion, a 20 removable metallic jacket arranged within and of different material from the body portion, a collar connected with the body portion and supporting the lower end of the jacket, said body portion having its top 25 formed with a laterally continuous flange formed with a ledge, and a hollow metallic head removably mounted on said ledge.

2. A mold for the purpose set forth comprising a hollow metallic body portion, a 30 removable metallic jacket arranged within and of different material from the body portion, a collar connected with the body portion and supporting the lower end of the jacket, said body portion having its top 35 formed with a laterally continuous flange formed with a ledge, and a hollow metallic head removably mounted on said ledge, the walls of said body portion gradually decreasing in thickness from the bottom there- 40 of to said flange.

3. A mold for the purpose set forth comprising a hollow metallic body portion, a removable metallic jacket arranged within and of different material from the body 45 portion, a collar connected with the body portion and supporting the lower end of the jacket, said body portion having its top 50 formed with a laterally continuous flange formed with a ledge, and a hollow metallic head removably mounted on said ledge, and lateral lugs projecting from the body portion below said flange and provided with lifting yokes.

4. A mold for the purpose set forth comprising a hollow metallic body portion, a removable metallic jacket arranged within and of different material from the body portion, a collar connected with the body portion and supporting the lower end of the 55 jacket, said body portion having its top 60 formed with a laterally continuous flange formed with a ledge, and a hollow metallic head removably mounted on said ledge, the walls of said body portion gradually decreasing in thickness from the bottom there- 65 of to said flange.

of to said flange, and lateral lugs projecting from the body portion below said flange and provided with lifting yokes.

5. A mold for the purpose set forth comprising a hollow metallic body portion, a 70 removable metallic jacket arranged within and of different material from the body portion, a collar connected with the body portion and supporting the lower end of the jacket, said body portion having its top 75 formed with a laterally continuous flange formed with a ledge, and a hollow metallic head removably mounted on said ledge, and upwardly extending yokes projecting from said head.

6. A mold for the purpose set forth comprising a hollow metallic body portion, a removable metallic jacket arranged within and of different material from the body portion, a collar connected with the body 85 portion and supporting the lower end of the jacket, said body portion having its top formed with a laterally continuous flange formed with a ledge, and a hollow metallic head removably mounted on said ledge, the 90 walls of said body portion gradually decreasing in thickness from the bottom there- of to said flange, and upwardly extending yokes projecting from said head.

7. A mold for the purpose set forth comprising a hollow metallic body portion, a removable metallic jacket arranged within and of different material from the body portion, a collar connected with the body portion and supporting the lower end of the 100 jacket, said body portion having its top 105 formed with a laterally continuous flange formed with a ledge, and a hollow metallic head removably mounted on said ledge, and lateral lugs projecting from the body portion below said flange and provided with lifting yokes, and upwardly extending yokes projecting from said head.

8. A mold for the purpose set forth comprising a hollow metallic body portion, a removable metallic jacket arranged within and of different material from the body portion, a collar connected with the body portion and supporting the lower end of the jacket, said body portion having its top 110 formed with a laterally continuous flange formed with a ledge, and a hollow metallic head removably mounted on said ledge, the 115 walls of said body portion gradually decreasing in thickness from the bottom there- of to said flange, and lateral lugs projecting from the body portion below said flange and provided with lifting yokes, and upwardly extending yokes projecting from said head.

9. A mold for the purpose set forth comprising a hollow metallic body portion, a removable metallic jacket arranged within and of different material from the body portion, a collar connected with the body 130

portion and supporting the lower end of the jacket, said body portion having its top formed with a laterally continuous flange formed with a ledge, and a hollow metallic head removably mounted on said ledge, said body portion having the upper part thereof formed with an inwardly arranged continuous ledge, and said jacket having its top edge flush with said inwardly arranged ledge.

10. A mold for the purpose set forth comprising a hollow metallic body portion, a removable metallic jacket arranged within and of different material from the body portion, a collar connected with the body portion and supporting the lower end of the jacket, said body portion having its top formed with a laterally continuous flange formed with a ledge, and a hollow metallic head removably mounted on said ledge, the walls of said body portion gradually decreasing in thickness from the bottom thereof to said flange, said body portion having the upper part thereof formed with an inwardly arranged continuous ledge, and said jacket having its top edge flush with said inwardly arranged ledge.

11. A mold for the purpose set forth comprising a hollow metallic body portion, a removable metallic jacket arranged within and of different material from the body portion, a collar connected with the body portion and supporting the lower end of the jacket, said body portion having its top formed with a laterally continuous flange formed with a ledge, and a hollow metallic head removably mounted on said ledge, and lateral lugs projecting from the body portion below said flange and provided with lifting yokes, said body portion having the upper part thereof formed with an inwardly arranged continuous ledge, and said jacket having its top edge flush with said inwardly arranged ledge.

12. A mold for the purpose set forth comprising a hollow metallic body portion, a removable metallic jacket arranged within and of different material from the body portion, a collar connected with the body portion and supporting the lower end of the jacket, said body portion having its top formed with a laterally continuous flange formed with a ledge, and a hollow metallic head removably mounted on said ledge, the

walls of said body portion gradually decreasing in thickness from the bottom thereof to said flange, and lateral lugs projecting from the body portion below said flange and provided with lifting yokes, said body portion having the upper part thereof formed with an inwardly arranged continuous ledge, and said jacket having its top edge flush with said inwardly arranged ledge.

13. A mold for the purpose set forth comprising a hollow metallic body portion formed with a lateral flange at the top thereof and further formed with an inwardly arranged continuous ledge at the top thereof, a metallic jacket arranged within said body portion, projecting below the bottom thereof and flush with said ledge, said jacket formed of material different from that of the body portion, a collar inclosing the projecting portion of said jacket and connected with said body portion, and a removable metallic head supported by said flange.

14. A mold for the purpose set forth comprising a hollow metallic body portion formed with a lateral flange at the top thereof and further formed with an inwardly arranged continuous ledge at the top thereof, a metallic jacket arranged within said body portion projecting below the bottom thereof and flush with said ledge, said jacket formed of material different from that of the body portion, a collar inclosing the projecting portion of said jacket and connected with said body portion, and a removable metallic head supported by said flange.

15. A mold for the purpose set forth comprising a hollow body portion having an inwardly arranged ledge near the top thereof and further having an outwardly extending flange at the top thereof, lifting means for said body portion arranged below said flange, a removable hollow head supported by said flange, a jacket arranged within said body portion flush with said ledge and projecting below the bottom of said body portion, and a collar supporting the projecting portion of the jacket and connected to said body portion.

In testimony whereof I affix my signature.

BERNARD B. BRASZKOWSKI.
